UNITED STATES PATENT OFFICE.

KARL ARNSTEIN, OF FRIEDRICHSHAFEN-ON-THE-BODENSEE, GERMANY, ASSIGNOR
TO THE FIRM LUFTSCHIFFBAU ZEPPELIN GESELLSCHAFT MIT BESCHRÄNKTER
HAFTUNG, OF FRIEDRICHSHAFEN-ON-THE-BODENSEE, GERMANY.

AIRSHIP HULL.

Application filed July 16, 1923. Serial No. 651,952, and in Germany August 21, 1922.

My invention refers to improvements in the construction of the hulls of air craft and it particularly refers to the wire netting which partly fills the quadrangular or rhomboid gaps formed in the metallic structure or hull of rigid airships by the combination of longitudinal and transverse members, such wire netting serving the purpose of confining the envelopes of the gas cells within the metallic frame and preventing an excessive expansion of the cells.

It is an object of my invention to provide for a better distribution of the stresses and of the transmission of forces in the metallic structure than it was possible to accomplish heretofore.

Up till now the panels formed in the metallic structure have been provided with a loose wire netting secured at several points to the longitudinal and transverse members in order to restrict the bulging and expansion of the gas cells which bear from the inside against the frame and the wire netting. The wire netting heretofore in use transmits the forces generated by the gas pressure onto the longitudinal members. Thus the longitudinal members have to absorb the differences of the gas pressures of two adjacent panels by lateral flexion. This strain, however, constitutes a great inconvenience for the longitudinal supporting members which are moreover exposed to a considerable crushing strain for the reason that the other strains referred to run in the direction of the smaller width of the supporting structure. Furthermore, this method of construction necessitates an exceedingly large number of wire fastening points on the longitudinal members.

These inconveniences are avoided according to my invention by so arranging the wire fastening points that they become situated exclusively at the points of intersection and fixation of the longitudinal and transverse supports. Wherever it becomes necessary for the purpose of a more perfect subdivision of the panels to intersectingly arrange wires on the freely exposed panel portions and on the supporting beams, the wires are mounted according to this invention so as to be displaceable in the longitudinal direction upon the intersected members, that is to say, they are only laterally guided, so that in view of the unobstructed guiding of the members

the strains to which the wire is subjected in two adjoining panels, may be compensated, and lateral stresses upon the intersected members are prevented.

In order to produce a satisfactory subdivision of the panels the wires may be deflected laterally by interlacing intersecting wires.

It is preferable, when attaching the wires to the frame, to temporarily insert a spring which, in being compressed, provides for the required slackness of the wires.

The invention will be more particularly described with reference to the accompanying drawing illustrating diagrammatically by way of example parts of an airship skeleton frame embodying the principles of this invention.

Figs. 1 to 4 of the drawings are perspective plans representing 4 different examples of making use of my invention. Fig. 5 is a diagonal cross section taken on line A—A of Fig. 1.

In the drawings Figure 1 is a perspective plan showing longitudinal supporting members a^1 , a^2 , ring-shaped transverse members b^1 and b^2 . Two slack wires c and d are secured only at the points of intersection and fixation of the longitudinal and transverse members by means of eyes e .

Figure 2 is distinguished from Figure 1 by the wires c and d being jointed or interlaced at f , and being thereby deflected, so that an additional pair of wires c^1 , d^1 may be inserted which is interlaced or jointed at f^1 in a similar manner.

In the form shown in Figure 3 the wires extend across two panels. Three longitudinal members a^1 , a^2 , a^3 intersect and are fixed to two ring-shaped transverse members b^1 , b^2 . The wire g extends from the point of fixation a^1 , b^1 to the point of fixation a^3 , b^2 and across the longitudinal member a^2 , and is displaceably guided at i on such support. The wire h extends from a^1 , b^2 to a^3 , b^1 and likewise intersects the longitudinal member a^2 , and is guided thereon in the same manner, so that there is the possibility of a compensation of tensions in both wires, g and h , across the longitudinal member a^2 . The wires starting at the points of intersection of the members b^1 and b^2 with the member a^2 are only partially shown. They extend in a manner similar to the other wire; they

are also laterally guided upon the longitudinal members a^1 and a^3 respectively.

Figure 4 shows a form in which the slack wires are made to extend across three panels. Moreover, for the purpose of producing a satisfactory subdivision, always two wires extend from one corner and they are laterally deflected at the points of intersection with the longitudinal members. The four longitudinal members a^1, a^2, a^3, a^4 , are fixed to the two ring-shaped members b^1, b^2 respectively at the points of intersection. The points a^1, b^1 , and a^4, b^2 are connected by diagonal wires k^1 and k^2 . On the transverse members a^2 and a^3 these two wires are loosely guided in plates i , so as to be laterally held to the longitudinal members, and are deflected out of the diagonal direction. In the same manner the pair of diagonal wires l^1 and l^2 connecting the points of intersection a^1, b^2 and a^4, b^1 , respectively, is deflected in guides i on the longitudinal members a^2 and a^3 .

In Figure 5 a diagonal cross section on the line A—A of Figure 1, is shown on a somewhat enlarged scale.

The two longitudinal members a^1 and a^2 are provided at the points where they intersect with transverse members with eyes e to which the wires c are secured. The wire c is slack so as to allow of a corresponding bulging of the envelope n of the filled gas cell.

Various other constructions and modifications are within the scope of this invention, and will suggest themselves in accordance with varying conditions of applications of the invention, and without deviating from the spirit thereof, as pointed out in the claims. More particularly the term "wire" shall include also non-metallic tension means such as strings and the like.

I claim:

1. A rigid airship hull comprising a plurality of longitudinal members, transverse members intersecting said longitudinal members and wires extending between points of intersection of said longitudinal members with said transverse members, said wires crossing one of said longitudinal members and means slidably supporting and guiding said wires against lateral movement on said crossed longitudinal member.

2. A rigid airship hull comprising a plurality of longitudinal members, transverse members intersecting said longitudinal members, wires extending between points of intersection of said longitudinal members with said transverse members, and means for deflecting said wires longitudinally of said hull.

3. A rigid airship hull comprising a plurality of longitudinal members, transverse members intersecting such longitudinal members, wires extending between points of

intersection of said longitudinal members with said transverse members, and means for guiding said wires intermediate the points of intersection and for deflecting said wires longitudinally of said hull.

4. A rigid airship hull comprising a plurality of longitudinal members, transverse members intersecting such longitudinal members, wires extending between points of intersection of said longitudinal members with said transverse members, said wires crossing one of said longitudinal members and means for guiding said wires against lateral movement and for deflecting said wires on said crossed longitudinal members.

5. A rigid airship hull comprising substantially reticularly intersecting longitudinal and transverse ring-shaped supporting members, gas cells at the inside of said supporting members, and wires diagonally connecting points of intersection and tensionally and slidably mounted on intermediate supporting members and deflectingly intersecting each other upon the exposed portions of said gas cells.

6. A rigid airship hull comprising substantially reticularly intersecting longitudinal and transverse ring-shaped supporting members, gas cells at the inside of said supporting members, wires diagonally connecting points of intersection and displaceably mounted on intermediate supporting members and interlacingly and deflectingly crossing each other upon the exposed portions of said gas cells intermediate the neighboring supporting members.

7. A rigid airship hull comprising substantially reticularly intersecting longitudinal and transverse ring-shaped supporting members, gas cells mounted at the inside of said members, deflecting means supported on said supporting members and intermediate thereof, and wires diagonally connecting points of intersection of said supporting members and having a length in excess of the distance thereof and deflectingly and tensionally mounted on said deflecting means.

8. A rigid airship hull having a gas cell therein, comprising a plurality of rigid longitudinal members distributed over the circumference of the hull, rigid transverse members also distributed over the circumference of the hull and intersecting the longitudinal members, and wires for supporting the circumferential walls of the cell and connected at intersections of the longitudinal and transverse members, said wires being connected at points in said intersection materially spaced from the outer surface contour of the hull superstructure, said wires being disposed in the circumferential hull structure adjacent the circumferential surface of the gas cell.

In testimony whereof I affix my signature.
KARL ARNSTEIN.
